UNITED STATES PATENT OFFICE.

HOWARD F. MARSTON AND JOHN L. McKITTRICK, OF DAYTON, OHIO; SAID McKITTRICK
ASSIGNOR TO SAID MARSTON.

CENTERING MECHANISM.

1,134,145.

Specification of Letters Patent. Patented Apr. 6, 1915.

Application filed August 1, 1912. Serial No. 712,662.

To all whom it may concern:

Be it known that we, HOWARD F. MARSTON and JOHN L. McKITTRICK, citizens of the United States, and residing, respectively, at 5 Dayton, in the county of Montgomery and State of Ohio, have invented certain new and useful Improvements in Centering Mechanism, of which the following is a specification.

10 This invention relates to centering mechanism for type or matrices and has for its object to provide means simple in construction and reliable in operation for centering lines of type of various lengths relatively to 15 a primary line of matter or to a predetermined point in a given measure.

This mechanism is particularly applicable to linotype machines of the general character of those illustrated, for instance, in 20 United States Patents 565,484 and 565,487 of August 11, 1896 to Mergenthaler.

The drawings accompanying this specification illustrate our improvements in their preferred embodiment as applied to such 25 machines.

Figure 1 is a front elevation of our improvements together with so much of a linotype machine as will serve to illustrate their application thereto. Fig. 2 is a plan view 30 corresponding therewith. Fig. 3 is a perspective elevation illustrating details of our improvements. Fig. 4 is a fragmentary detail elevation illustrating the operation of some other parts. Fig. 5 is a plan view of a 35 plurality of lines of type in which the composed matter has been centered by our improved mechanism. Fig. 6 is a fragmentary sectional elevation illustrating the operation of a portion of our improved mechanism.

40 At 2 is shown the usual guiding and forwarding mechanism for the matrices and at 3 is a line of matrices assembled in the usual elevator 4. Assembler finger 5 fixed to shifter rod 6 is preferably of equal length 45 with sliding assembler finger 7 and is connected thereto by pull spring 8 so that when the said finger 7 is released to slide endwise on shifter rod 6 it will be urged toward finger 5. Said finger 5 is chamfered at its 50 lower end 9 so that as the matrices in elevator 4 are moved upwardly they will enter between said fingers 5 and 7. For holding finger 7 in its idle position we provide hook

10 for engagement with pin 11 on hub 12 of said finger 7.

55 Hook 11 is adjustably held in the upper end of rod 13 mounted for oscillation in suitable brackets on frame 14 of the machine. Adjustably fixed to said rod 13 is dog 15 having angled face 16 for engagement with horn 17 of elevator 4. The usual elevator 18 for lowering the matrices to the mold, indicated at 19, is slidably mounted on frame 20 under gibs 21. As the composed line of matrices is moved downwardly by elevator 18 said line is delivered between faces 22 of vise jaws 23, 24, which faces are normally separated from one another the maximum amount, Fig. 3, by means of lever slides 25, 26, respectively.

60 Vise jaws 23, 24, are slidably mounted in channels in frame 20 and are held therein by said lever slides 25, 26.

65 Lever slides 25, 26 are fixed in lever slide base 27 and reach upwardly therefrom preferably at equal opposite angles thereto. In the illustrated embodiment said angle is about forty-five degrees to said base and said slides stand at about ninety degrees 70 from each other.

75 Vise jaws 23, 24, are provided with angular slots as 28 in jaw 23 and 29 in jaw 24 for the reception of said lever slides. Therefore, if base 27 is moved toward said jaws, lever slides 25, 26 will engage slots 28, 29 in 80 jaws 23, 24, respectively, and move those jaws in their slideways in frame 20, toward one another to grip a line of matrices therebetween. Said slide base 27 is slidably mounted for purposes of adjustment on bar 30 thereunder. Base 27 is preferably provided with overhanging edges 31 for guidance on bar 30 and said bar is slotted at 32 for the passage therethrough of screw 33 threaded into base 27. Spring 34 between 85 the head of screw 33 and the bottom of bar 30 serves to hold base 27 and bar 30 in frictional engagement. Bar 30 may be moved up and down to actuate jaws 23, 24, toward and from each other through the instrumentality of lever slides 25, 26, by means of rods 45, 46 commonly known in this class of machines as justification rods. These rods will be moved up in unison so as to maintain parallelism between bar 30 and jaws 100 23, 24.

- Outreaching to the left from jaw 23 is vise jaw adjusting rod 35 for engagement with operating lever 36 pivoted at 370 in bracket 380 outreaching from frame 20.
- 5 Pivoted to operating lever 36 is arm 37 for movement into and out of operative position relatively to vertically movable actuator 38. Said actuator may be moved upwardly, Figs. 1 and 3, at suitable times by well-known automatic means not shown. It is obvious, however, that it may be actuated by hand if desired. For swinging arm 37 into and out of operative relation to actuator 38 we provide the following means:
- 10 15 Rotatably mounted in ears 39, 40, outstanding from frame 20 is rod 41. To that end of said rod adjacent to elevator 4 is fixed handle 42 convenient for the operator of the machine. To the other end of said rod is fixed upstanding arm 43, the upper end of which is connected to arm 37 by link 44.
- In the automatic operation of machines of the class to which the present improvements pertain actuator 38 is moved upwardly in suitable timing with the upward movement of elevator 18.
- 20 25 For automatically swinging arm 37 out of operative relation to actuator 38 after that actuator has engaged arm 37 for locating the first line of any given group of lines, at the extreme right, Fig. 5, relatively to the slug which is to be cast, I provide lug 56 on elevator 18 for engagement, as that elevator moves upwardly, with finger 55 fixed to rod 41.
- The operation of our improved mechanism is as follows: A composed line of matrices having been delivered to elevator 4 lever 50 is operated to raise that elevator, delivering said matrices between fingers 5 and 7. The continued upward movement of said elevator will bring horn 17 into engagement with the inclined face 16 of dog 15, whereby rod 13 will be rotated to withdraw hoop 10 from engagement with pin 11 permitting sliding finger 7 to move into engagement with the left hand end of the line of matrices 3, Fig. 1, clamping those matrices in close contact with each other and against finger 5. When elevator 4 has been raised to delivery position, shifter rod 6 will be moved to the left carrying said line of matrices therewith into guideway 47 and therethrough to elevator 18. The line of matrices still guided by fingers 5 and 7 will be delivered downwardly from said fingers to between faces 22 of jaws 23, 24. Rods 45, 46 then being moved upwardly, lever slides 25, 26, in engagement with vise jaws 23, 24, will cause those jaws to move inwardly in unison toward each other clamping the line of matrices therebetween and centering that line lengthwise relatively to a vertical line 60 65 through the jointure 49 of lever slides 25, 26. In the mean time shifter rod 6 has returned fingers 5 and 7 to their initial positions of Fig. 1. If it is now desired to position said line of matrices at a given point lengthwise the slug or linotype which is to be cast, as at the extreme right end thereof, Fig. 5, handle 42 is moved outwardly whereby rod 41 is rotated to move arm 37 into engaging position over the upper end of actuator 38. Thereupon said actuator is moved upwardly into engagement with arm 37 causing operating lever 36 to engage the end of rod 35, thereby sliding endwise to the right jaws 23, 24, the matrices therebetween and lever slides 25, 26 of base 27, against the frictional resistance of that base on bar 30. It will be observed that the matrices comprising any given line include no quads or spaces but are limited to the required characters. This permits the composed matter to be arranged in any desired position relatively to the slug length. Those portions of the slug as 60 which do not bear printing characters are cast against the faces of jaws 23, 24. It will thus be seen that with our improved mechanism it is unnecessary to drop any spaces or quads to fill out the lines of matrices, provision being made for said filling out in casting. The linotype slug may now be cast in the usual manner and the matrices returned to the reservoir according to means well-known in the art which are not necessary to describe herein. Our improved mechanism is now set for centering successive lines of matrices in coincidence with the line the centering of which has just been described. In the meantime actuator 38 has been returned to its idle position. During the upward return movement of elevator 18 for the delivery of the matrices to their reservoir, lug 56 on said elevator will encounter finger 55 thereby by rocking rod 41, Fig. 6, whereby arm 37 is swung out of engaging position relatively to actuator 38, Fig. 2. Thereafter each upward movement of actuator 38 will be an idle movement, without performing any useful work. Such idle operation of said actuator will continue until handle 42 is again pulled outwardly to move arm 37 into engaging position with said actuator, for positioning the matrices relatively to the primary line of the next group of lines.
- 40 45 50 55 60 65 70 75 80 85 90 95 100 105 110 115 120 125 130 Referring now particularly to Fig. 5, if it is desired to have several lines of type centered relatively to each other, located at the extreme end as 51 of the completed slugs, it will be necessary first to set and center the longest of the several lines to be thus associated. In the illustrated arrangement the second line 52 is that longest line. Such longest line can be readily selected from the copy by inspection and the assembled matrices therefor delivered to the extreme right by means of actuator 38, as already de-

scribed. The other lines to be associated therewith can then be set up and cast in any sequence desired and, after casting, the slugs can be arranged in proper order for printing.

5 We claim:

1. Centering mechanism for a line of type including in combination, a pair of oppositely disposed type engaging jaws, means for moving said jaws toward and from each other, and means for adjusting said jaws and their moving means lengthwise said jaws without disturbing the relation of the jaws to each other or to their moving means.

10 2. Centering mechanism for a line of type including in combination, a pair of oppositely disposed type engaging jaws, means for moving said jaws toward and from each other in predetermined ratios relatively to a fixed point therebetween, means for adjusting said jaws and their moving means lengthwise said jaws without disturbing the relation of the jaws to each other or to their moving means, and means for holding said jaws and their moving means in their adjusted position.

15 3. Centering mechanism for a line of type including in combination, a pair of oppositely disposed type engaging jaws, means for moving said jaws toward and from each other in synchronism, means for adjusting said jaws and their moving means lengthwise said jaws without disturbing the relation of the jaws to each other or to their moving means, means for holding said jaws and their moving means in their adjusted position, means for assembling a plurality of type to form a composed line and means for delivering said composed line between said oppositely disposed jaws.

20 4. Centering mechanism for a line of type including in combination, a pair of oppositely disposed type engaging jaws, a pair of relatively rigid lever slides for engagement with said jaws for moving said jaws toward and from each other, and means for actuating said lever slides for moving said jaws.

25 5. Centering mechanism for a line of type including in combination, a pair of oppositely disposed type engaging jaws, a pair of lever slides for moving said jaws toward and from each other, means for actuating said lever slides for moving said jaws, and means for adjusting said jaws and their moving means lengthwise said jaws without disturbing the relation of the jaws to each other or to their moving means.

30 6. Centering mechanism for a line of type including in combination, a pair of oppositely disposed type engaging jaws, a pair of lever slides for moving said jaws toward and from each other, means for actuating said lever slides for moving said jaws, and means operatively connected with one of said jaws

for adjusting said jaws in the line of their length without disturbing their positions relatively to each other or to their moving means.

7. Centering mechanism for a line of type including in combination, a pair of oppositely disposed type engaging jaws, a pair of lever slides for moving said jaws toward and from each other, means for actuating said lever slides for moving said jaws, means for adjusting said jaws and their moving means lengthwise said jaws without disturbing the relation of the jaws to each other or to their moving means, a lever slide base in which said lever slides are fixed, a lever slide bar mounted for movement toward and from said vise jaws and means for moving said lever slide bar.

75 8. Centering mechanism for a line of type including in combination, a pair of oppositely disposed type engaging jaws, a pair of lever slides for moving said jaws including a lever slide base in which said lever slides are fixed, a lever slide bar mounted for movement toward and from said vise jaws, said lever slide base being mounted on said lever slide bar for adjustment parallel with the movement of said vise jaws, means for maintaining the adjustment between said lever slide base and lever slide bar, and means for moving said lever slide bar.

80 9. Centering mechanism for a line of type including in combination, a pair of oppositely disposed type engaging jaws, a pair of relatively rigid angularly disposed lever slides for moving said jaws toward and from each other, means for actuating said lever slides for moving said jaws, means for assembling a plurality of type to form a composed line, and means for delivering said composed line between said oppositely disposed jaws.

85 10. Centering mechanism for a line of type including in combination, a pair of oppositely disposed type engaging jaws, a pair of lever slides for moving said jaws toward and from each other, means for actuating said lever slides for moving said jaws, means operatively connected with one of said jaws for adjusting said jaws in the line of their length without disturbing their positions relatively to each other or to their moving means, means for assembling a plurality of type to form a composed line and means for delivering said composed line between said oppositely disposed jaws.

90 11. Centering mechanism for a line of type including in combination, a pair of oppositely disposed type engaging jaws, a pair of lever slides for moving said jaws toward and from each other, means for actuating said lever slides for moving said jaws including a lever slide base in which said lever

- 4
- slides are fixed, a lever slide bar mounted for movement toward and from said vise jaws, means for moving said lever slide bar, means for assembling a plurality of type to form a composed line, and means for delivering said composed line between said oppositely disposed jaws.
12. Centering mechanism for a line of type including in combination, a pair of oppositely disposed type engaging jaws, a pair of lever slides for moving said jaws toward and from each other, means for actuating said lever slides for moving said jaws including a lever slide base in which said lever slides are fixed, a lever slide bar mounted for movement toward and from said vise jaws, said lever slide base being mounted on said lever slide bar for adjustment parallel with the movement of said vise jaws, means for maintaining the adjustment between said lever slide base and lever slide bar, means
- for moving said lever slide bar, means for assembling a plurality of type to form a composed line, and means for delivering said composed line between said oppositely disposed jaws. 25
13. Centering mechanism for a line of type including in combination a pair of oppositely disposed type engaging jaws each having an angular slot therein, a pair of relatively rigid angularly disposed lever slides in engagement with said angular slots respectively, and means for actuating said lever slides for moving said jaws. 30

Correction in Letters Patent No. 1,134,145.

It is hereby certified that in Letters Patent No. 1,134,145, granted April 6, 1915, upon the application of Howard F. Marston and John L. McKittrick, of Dayton, Ohio, for an improvement in "Centering Mechanism," an error appears in the printed specification requiring correction as follows: Page 3, line 123, for the syllables "sately" read *oppositely*; and that the said Letters Patent should be read with this correction therein that the same may conform to the record of the case in the Patent Office.

Signed and sealed this 17th day of August, A. D., 1915.

[SEAL.]

J. T. NEWTON,
Acting Commissioner of Patents.
